UNITED STATES PATENT OFFICE.

ROBERT H. FOSTER, OF UNION COURSE, LONG ISLAND, NEW YORK.

MUSIC-TURNER.

No. 852,944.

Specification of Letters Patent.

Patented May 7, 1907.

Application filed June 1, 1906. Serial No. 319,664.

To all whom it may concern:

Be it known that I, ROBERT H. FOSTER, a citizen of the United States, residing at Union Course, Long Island, in the county of Queens and State of New York, have invented certain new and useful Improvements in Music-Turners, of which the following is a specification, such as will enable those skilled in the art to which it appertains to make and use the same.

This invention relates to sheet music turning devices, and the object thereof is to provide an improved device of this class which is designed to be mounted on or connected with a piano, organ or similar instrument, and which is simple in construction and operation, and by means of which successive leaves of music may be conveniently turned whenever desired.

20 The invention is fully disclosed in the following specification, of which the accompanying drawing forms a part, in which the separate parts of my improvement are designated by suitable reference characters in each of the views, and in which:

Figure 1 is a front view of my improved sheet music turning device; Fig. 2 a sectional plan on the line 2—2 of Fig. 1; Fig. 3 a partial section on the line 3—3 of Fig. 1; Fig. 4 a plan view of the top of that part of the device shown in Figs. 1 and 3; Fig. 5 a side view of a finger disk which forms a part of my improved music sheet turning device, and showing the support thereof in section; Fig. 6 a top plan view of the device shown in Fig. 5; Fig. 7 a bottom plan view of the finger disk shown in Fig. 5; Fig. 8 an edge view of a clamp which I employ; and, Fig. 9 a plan view of the end portion of one of the turning arms of the device.

In the practice of my invention I provide a base *a* to which is secured an oblong box or case *a*² which, as shown in Fig. 1, is open at the front, but which may be closed if desired, and the base *a* is provided with a recess or chamber *a*³ at one side of the central portion thereof.

The top of the box or case *a*² is provided with a sleeve or collar *a*⁴ in which is secured 50 a vertical tube *a*⁵, and passing vertically through the tube *a*⁵ is a rod *c* on which is mounted a plurality of rotatable tubes *d* each of which is provided at the bottom thereof with a grooved wheel *d*², and the bottom of the rod *c* is provided with a similar wheel *c*².

The lower end of the rod *c* and the lower ends of the tubes *d* together with the wheel *c*² and the wheels *d*² are within the box or case *a*, and each of said wheels is provided with a spring *e* secured in the right hand end 60 of said box or case, and the other end of which is provided with an extension or cord *e*² secured in the groove of the corresponding wheel *d*² or *c*². The wheels *d*² and *c*² are also provided in the perimeter thereof with a 65 notch or recess *f*, and secured in the left hand end of the box or case *a*² are a plurality of spring arms *f*² which equal in number the wheels *c*² and *d*² and the free ends of which bear in the notches or recesses *f* of said wheels 70 as clearly shown in Fig. 2.

Mounted in the recess or chamber *a*³ of the base *a* is a finger disk *g* provided with a plurality of upwardly directed fingers *g*² which equal in number the spring arms *f*² and 75 wheels *c*² and *d*², and the fingers *g*² differ in length as clearly shown in Fig. 5, and the shortest finger *g*³ is adapted to operate the bottom spring arm *f*², the next longer finger the succeeding bottom spring arm *f*² and so 80 on, the longest finger connected with the disk *g* being adapted to operate the top spring arm *f*².

The finger disk *g* is also provided on the bottom thereof with a plurality of teeth *g*⁴ 85 all of which are inclined in the same direction, and said finger disk is secured to a sleeve *g*⁵ mounted on a pin *g*⁶ secured in the recess or chamber *a*³ in the base *a*. Mounted on the sleeve *g*⁵ below the disk *g* is an arm *g*⁸ 90 provided with a collar through which said sleeve passes, said collar being clearly shown in Fig. 5 and being also marked *g*⁷, and wound on the sleeve *g*⁵ below the arm *g*⁸ is a spring *g*⁷ one end of which is secured in the bottom of the recess or chamber *a*³ and the other end of which is secured to the arm *g*⁸. The arm *g*⁸ does not show in Fig. 5 but the collar thereof does show, and said arm and its collar are clearly shown in Fig. 1.

Connected with the upper end of each of the tubes *d* and with the upper end of the rod *c* is an arm *h*, and said arms are each provided at their outer end with a clamp *h*², and these clamps are preferably connected with 105 the arms *h* as shown in Fig. 9, this connection being made by means of spiral springs *h*³ and *h*⁴ whereby said clamps are suspended by means of said springs, the object of this being to prevent the clamps from twisting or 110

bending the sheets of music in the operation of the device as hereinbefore described.

In the operation of this device the arms *h* are all first turned to the right as shown in Fig. 1 in which position the spring arms *f*² engage the corresponding wheels *d*² and *c*², and the springs *e* are put under tension. The sheets of music to be turned are then placed in an upright position and the clamps *h*² are connected with the top edges thereof at or near the outer corners thereof. In this position of the parts the fingers *g*² of the finger disk *g* is directly back of the bottom spring arm *f*², and if now the arm *g*² be turned to the left said arm will engage one of the teeth *g*⁴ on the finger disk *g* and said disk will be turned to the left, the bottom spring arm *f*² will be disengaged from the corresponding wheel *c*² and the spring *e* connected with the wheel *c*² will turn said wheel to the right and the arm *h* connected with the top of the rod *c* will be turned to the left and carry with it the sheet of music connected therewith.

When the arm *g*² is released the spring *g*⁷ throws said arm back into the position shown in Fig. 1, and in the next movement of the arm *g*² to the left the finger disk *g* will be operated as above described, and the second spring arm *f*² from the bottom will be released from the corresponding wheel *d*², and the inner tube *d* will be turned to the right and the arm *h* connected therewith will be thrown over to the left, and the sheet of music connected therewith will be turned as will be readily understood. In this way by each successive movement of the arm *g*² the wheels *c*² and *d*² beginning with the bottom wheel *c*² may be successively turned and the arms *h* connected with the rod *c* and tubes *d* counting from the rod *c* outwardly will be turned in the manner hereinbefore described.

The arm *g*² may be of any preferred construction but is preferably made of spring metal so that it will bend freely over the inclined surface of the teeth *g*⁴ when said arm is moved into its normal position by the spring *g*⁷.

It will be understood that when the arms *h* have all been turned to the left, they must, before the device can again be operated, be turned back to the right or into the position shown in Fig. 1, by hand, and this operation puts the springs *e* under tension and enables the spring arms *f*² to engage the notches or recesses *f* in the perimeter of the wheels *c*² and *d*², after which the device may be again

operated for turning the sheets of music as hereinbefore described.

In the accompanying drawing I have shown seven music turning arm carriers including the rod *c* and six of the tubes *d*, a wheel connected with said rod and each of said tubes, springs *e* equaling the number of wheels *d*² and *c*², and spring arms *f*² equaling the number of said wheels, but it will be apparent that any desired number of arms *h* may be employed in which event the other parts of the device will be similarly regulated.

Having fully described my invention, what I claim as new and desire to secure by Letters Patent is:—

1. A music sheet turner comprising a base, concentrically placed upright members each of which is provided at its upper end with a music turning arm, said upright members being each provided at its lower end with a wheel, tension springs connected with said wheels and adapted to turn them in one direction, said wheels being also provided each with a notch or recess in the perimeter thereof, spring arms adapted to engage said notches or recesses and hold said wheels against the operation of the tension springs, and means for successively releasing the spring arms from said wheels, consisting of a disk mounted below said spring arms and provided with upwardly directed fingers of varying lengths and on the bottom thereof with teeth, and a spring arm mounted below said disk and adapted to engage said teeth.

2. A music sheet turner comprising a base, upright concentrically arranged rotatable devices connected therewith and provided at their upper ends with arms having clamps, said rotatable devices being also provided at their lower ends with wheels, tension springs connected with said wheels, spring arms adapted to engage the perimeter of said wheels, and means for successively releasing said spring arms from said wheels, consisting of a disk mounted in the base and provided with upwardly directed fingers of varying lengths and on the bottom thereof with a plurality of teeth, and a spring arm mounted below said disk and adapted to engage said teeth.

In testimony that I claim the foregoing as my invention I have signed my name in presence of the subscribing witnesses this 31st day of May 1906.

ROBERT H. FOSTER.
